UNITED STATES PATENT OFFICE.

ORVILLE M. MORSE, OF JACKSON, MICHIGAN; SARAH G. MORSE SPECIAL ADMINISTRATRIX OF SAID ORVILLE M. MORSE, DECEASED.

DUST-COLLECTOR.

1,029,214.

Specification of Letters Patent. Patented June 11, 1912.

Application filed October 9, 1905. Serial No. 281,927.

To all whom it may concern:

Be it known that I, ORVILLE M. MORSE, a citizen of the United States, residing at Jackson, in the county of Jackson and State of Michigan, have invented certain new and useful Improvements in Dust-Collectors, of which the following is a specification.

My invention relates to centrifugal dust collectors, and has for its general object to provide a machine of the character specified, wherein the leakage of dust from the air outlet is reduced to a very small quantity, and the back pressure at the same time minimized. To these ends I provide in general a machine wherein air is introduced at the upper part of the structure into an area of eccentric plan configuration, relative to the casing axis, wherein it may establish a vertical whirl, and by the encompassing walls whereof the air is directed into operative proximity to an air outlet opening to escape therethrough, there being provided without the eccentric whirl area, and communicating with the periphery of said whirl area, an air-flow space wherein air flows in a rotary direction concentric with the casing axis; such flow being occasioned by the influence of the dominant or primary eccentric whirl, and there being provided further a lower conical whirl area in the casing, preferably concentric with the casing axis and communicating with both the eccentric whirl area and the said air-flow space, so that dust introduced into the machine with the air, or a major portion of such dust, is centrifugally directed into and maintained against retrogression from the air-flow space without the eccentric whirl area, whence it descends through the sub-jacent conical whirl space under the influence of the whirl therein, to the dust escape outlet at the apex of the cone.

Other and further objects of my invention and features of novel construction may best be gathered from the following description, taken in conjunction with the accompanying drawing, wherein,

Figure 1 is a central vertical section of a machine embodying my invention, taken on line 1—1 of Fig. 2. Fig. 2 is a horizontal section taken on line 2—2 of Fig. 1, looking in the direction of the arrow. Fig. 3 is a detail of the outlet adjusting means. Fig. 4 is a section similar to Fig. 2 showing a modified embodiment of my invention. Fig. 5

is a similar view showing a different modified construction embodying my invention.

Throughout the drawings like numerals of reference refer always to like parts.

In general my machine comprising essentially a casing comprising a conical base or bottom structure having a dust outlet therein, a head structure having an air outlet in its deck, and an air-directing structure within the head of the casing into which opens, approximately tangentially, an air inlet, the air directing structure being arranged to direct air into a vertical whirl therein in an area into which the air-escape outlet opens, preferably at a point contiguous to the periphery of the whirl, and said air directing structure being provided with openings therein communicating with spaces within the casing exterior to the said vertical whirl area.

In the specific embodiment of my invention illustrated in Figs. 1 and 2, 10 indicates the conical bottom of the casing provided with the usual dust outlet 11 at the bottom thereof, and 12 indicates in general the head 80 of the casing. In the construction shown the head 12 is polygonal and preferably square in cross section, as may best be seen in Fig. 2, the side walls 12' thereof being disposed to form chords of the circle outlined by the top of the conical bottom 11, so that the area within the head is substantially a square inscribed within the circle formed by the top of the cone 10.

To effect the closure of the portion of the top of the cone lying without the area of the head 12, a deck 14 is provided for the top of the cone 10, whereon the walls 12' of the head are built, the deck 14 having an opening therein substantially coextensive with the plan area of the head 12.

15 indicates the deck of the head 12, having therein an air outlet 16.

Within the head of the casing, extending downward from the deck thereof is an air-directing structure generally indicated at 17, and composed of a plurality of plates 18, generally disposed to encompass a vertical whirl area and to direct the air in whirl therein into operative proximity to the air outlet 16, that it may freely escape therefrom.

19 indicates openings between the plate 18 establishing communication between the vertical whirl area 20 encompassed by the 110

air-directing structure 17 and the exterior air-space 21, intermediate said air-directing structure and the casing.

21' indicates the angular spaces at the corners of the casing wherein eddies form by reason of the shape of the casing.

22—22 indicates eddy-forming means in the corners of space 21, said means being shown as rods grouped in the corners and depending from the deck.

23 is an air inlet opening tangentially into the air-deflecting structure 17, the inlet spout being closed at sides and bottom, to the end 23' of the spout, where commences the deflector structure 17, the plates 18 of sections 18 whereof extend in a generally circular form, each plate being preferably laterally out of register with the adjoining plates, with its outer end at a slightly greater radial distance from the center of the casing than the proximate end of the plate in advance thereof, so that the spaces 19 may be said to be tangential openings. Preferably the plates 18 are secured in any suitable manner to the deck at their rear ends (with reference to the direction of air travel) and at their forward ends are free for some lateral movement, means being preferably provided for moving said ends to vary the width of the openings 19. To this end I provide the bolts 24 secured to the free ends of the plates 18, and taking through the casing walls 12', said bolts being provided with the winged adjusting nuts 25. From its point of juncture with the wall of casing 12, the air-deflecting structure extends in a suitable curve, preferably terminating in a relatively short curve 17', to some point contiguous to the air escape outlet, the arrangement of the deflecting structure being such as to permit the formation of a vortical whirl within the area included therein, such vortical whirl being eccentric to the axis of the casing.

45 The space 21 without the whirl area aforesaid is preferably such as to permit air therein to flow in a path concentric with the casing axis except where interrupted by the inlet spout 23, the rectangular shape of the casing providing at the corners angular enlargements of the circle of air flow, as shown at 21' which constitute eddy spaces. The openings 19 affording communication between the air-flow space and the whirl area 55 within the directing structure 17 are preferably arranged to direct the air into the air-flow space at the points of closest proximity of the directing structure in the casing wall 12'.

60 At the point where the directing wall structure approaches the end of the inlet spout 22 there is preferably left a space 26, in which is preferably arranged a regulating plate 27 disposed at an angle and adjustable vertically. For simplicity the

plate 27 may be passed through a suitable slot cut in the deck of the casing, and held therein by frictional contact with the balls of the slot, adjustment being effected by withdrawing the strip partially from or introducing it farther into the interior of the casing.

Below the air-directing structure 17 within the casing, I preferably provide the inverted conical guard 28, preferably of less 75 diameter than the interior diameter of the square head, open at top 28' and bottom 28'', and suitably supported axially of the casing as by the arms 29—29 fastened to the deck 14 of the cone 10.

28' indicates a skinning opening in the guard 28, but any number of such openings may be provided, two being shown.

I also prefer that the outlet 16 be universally adjustable as to position, and to this end I form in the deck 15 of the casing, a concentric aperture 30, wherein is mounted for rotation an eccentric ring member 31, having therein an eccentric aperture 32, within which, in turn, is disposed for rotation the inner eccentric member 33 in which the outlet 16 is eccentrically formed. It will be apparent that by suitable adjustment of the double eccentric structure the position of the aperture 16 may be universally 95 adjusted within a certain range.

The action of the machine as shown above is as follows: Air introduced into the casing through the tangential inlet spout 22 strikes the air-directing structure 17 and is 100 deflected thereby into the whirl area 20 wherein it sets up a vortical whirl eccentric to the casing axis, its eccentricity being largely determined by the curvature of the air-directing wall and particularly the extremity 17' thereof. By said air-directing wall the air is brought into operative proximity of the air escape outlet 16 through which it freely escapes. It will be apparent that in its rotative and whirling movements the dust carried by the air, by reason of its greater persistence of motion than air, 110 masses against the directing structure, and at each of the outlets 19 accordingly a portion of the dust is projected into the exterior 115 air-flow space 21. In said space 21 there is set up an air-flow dominated by the whirl within the directing wall 20, said air-flow being generally in like direction with the direction of rotation with said whirl. The 120 dust carried by said air, in rotative flow, is centrifugally thrown outward, and tends to collect in the eddies 21' from which it falls into the lower portion of the casing, such action being aided to a degree by the provision of the rods 22 around and between which smaller eddies are further formed in which the dust is caught and permitted to fall. Thus the air which is diverted into 125 operative proximity to the outlet 16 is prac- 130

tically purified or freed from dust, and the air escaping into the air-flow space 21 is heavily dust laden.

The air whirl in the head of the casing above described causes to be formed in the chambers therebelow an air whirl substantially concentric with the casing axis, the guard 28 forming a sort of conical bottom for the upper eccentric whirl area, and preventing the distortion to any marked degree of the whirl within the conical bottom 10 of the casing under the domination of the vortical whirl in the head.

The distortion of the whirl axis from eccentric in the casing to concentric in the base tends to prevent the formation of such a rarefied condition in longitudinal alinement with the dust outlet as would tend to prevent free delivery of the dust or to cause light dust particles to ascend into the upper chamber after once being discharged therefrom.

In each of the eddies 21 the tendency of the air seems in practice to be to force its way downward, and adjacent the inlet the deflector 27 positively forces the dust laden air downward, so that the space below the deck 14 of the conical bottom is constantly receiving fresh increments of air, which prevents the accumulation at such points of dust masses, and I find in practice that the machine maintains itself clear of accumulated dust at such points. The dust thus dropping with the air from the eddy spaces 21 into the conical bottom 10 of the casing, descends spirally therein under the influence of the substantially concentric vortical whirl to the outlet 11 where it is discharged. Thus it will be seen that I provide a machine wherein the dust-laden air is caused to travel in a curved path from which open the tangential skimming-openings 19, of adjustable width, which serve to permit the passage there past of all of the massed dust before the end of the directing structure is reached, while a large portion of the air is projected at relatively high velocity into operative proximity to the air escape outlet 16 through which it freely escapes, and all the dust, forced into the air-flow space without the vorical whirl area, escapes from the eddy spaces or elsewhere, into the conical bottom of the machine, where, under the influence of the centrifugal vortical whirl, it descends to the dust escape outlet.

In Fig. 4 I have shown a modified construction wherein the inlet 23' opens angularly into the casing 12, though tangentially to the air-directing wall, and is provided with a side piece 23° pivoted to form a valve, movable by the adjustment of nut 23°, threaded on the bolt 23° extending from the valve through the inlet wall, to vary the size of the opening between the inner end

of the inlet spout and the air-deflecting structure 17.

In Fig. 5, a modified embodiment of my invention is shown wherein the casing is circular, the air-flow space 21^a being correspondingly approximately annular. The eddy creating means in such construction may comprise blocks or strips 22^a set vertically in the space 21^a to form obstructions therein.

While I have herein described in some detail specific embodiments of my invention it will be apparent that numerous changes might be made in the specific construction without departure from the spirit and scope of my invention.

Having thus described my invention, what I claim and desire to secure by Letters Patent, of the United States, is:

1. In a centrifugal dust collector, a decked casing, polygonal in plan, having an air outlet opening in its deck, and an inlet, a curved deflector structure depending from the deck and shorter than the casing making substantially a complete single turn about the casing axis, arranged to direct the incoming air into an eccentric whirl wholly within the lateral confines of the deflector structure and of relatively small diameter, the periphery whereof extends contiguous to and includes within it part of the air outlet opening, said deflector being arranged relative to the casing to provide between said parts an air flow space substantially surrounding the deflector, and provided with apertures through the deflector effecting communication between the whirl area and the air flow space, and a base structure below said decked casing having a dust outlet therein in open communication with all parts of the air flow space and whirl area.

2. In a centrifugal dust collector, a decked casing head polygonal in plan having therein an outlet, a tangential inlet, an apertured deflector completely surrounding the casing axis dividing the casing into an inner whirl area, and a surrounding air flow space communicating through the deflector apertures, said deflector depending from the casing deck and shorter than the casing and arranged to deflect the incoming air into a relatively small eccentric whirl including within its periphery part of the deck-outlet, and a conical casing member below the head in open communication with all parts of the head and having therein a dust outlet.

3. In a centrifugal dust collector, a casing comprising a head of polygonal, angular section, and a tapering base, an eccentric air directing structure in said head arranged to divert the incoming air into an eccentric vortical whirl, a tangential inlet to said whirl area, an air outlet from said whirl area, the directing structure provided with

openings communicating with the space intermediate said structure and the casing, a dust outlet in the bottom of the base and a conical guard below the eccentric vortical whirl area.

4. In a centrifugal dust collector, a casing comprising a head polygonal in cross section, a conical base in open communication with all parts of the head arranged 10 with its larger end to substantially circumscribe the bottom of the casing, a deflecting structure in the head arranged to deflect incoming air into an eccentric vortical whirl, said deflector having peripheral openings 15 therein, an air inlet, an air outlet opening into said whirl area, a dust outlet at the bottom of the cone, and a frusto-conical guard, open at both ends, disposed, small end down, below the vortical whirl area.

5. In a centrifugal dust collector, a casing 20 comprising a head and a tapering base in vertical coaxial alinement, an eccentrically curved air-directing structure in said head arranged to direct the incoming air into an eccentric vortical whirl, an inlet to the 25 whirl area, an air outlet from said whirl area, skimming openings in the air-directing structure, a dust outlet in the bottom of the base, and a conical guard below the eccentric whirl area, provided with a skim- 30 ming aperture therein.

In testimony whereof I hereunto set my hand in the presence of two witnesses.

ORVILLE M. MORSE.

In the presence of—

WILLIAM B. KNICKERBOCKER,
JOHN L. BENTLEY.
